UNITED STATES PATENT OFFICE.

DENTON K. SWARTWOUT, OF CLEVELAND HEIGHTS, OHIO.

VENTILATING SYSTEM.

1,271,494.

Specification of Letters Patent.

Patented July 2, 1918.

Application filed July 30, 1915. Serial No. 42,675.

To all whom it may concern:

Be it known that I, DENTON K. SWARTWOUT, a citizen of the United States, residing at Cleveland Heights, in the county of Cuyahoga and State of Ohio, have invented a certain new and useful Improvement in Ventilating Systems, of which the following is a full, clear, and exact description, reference being had to the accompanying drawings.

This invention relates to car ventilating systems, and has for its general object to provide for cars a system of ventilation which may be conveniently applied thereto without involving any material changes in the construction thereof—the ventilating system constituting my invention being capable of application as an attachment to existing cars. A further general object of the invention is to provide a ventilating system which can be applied to cars with a minimum of expense but which will, nevertheless, operate with a maximum of efficiency. Further and more limited objects of the invention are to provide for cars a ventilating system which is operated by induced draft, when the car is running in either direction; to distribute the entering air into the aisles without exposing the passengers to chilling drafts or otherwise incommoding them; to provide such systems with means whereby the incoming air may be sufficiently warmed to overcome the chilling effect thereof; also to discharge the air through the lavatories and closets in such manner as to prevent the dissemination of odors. With the foregoing objects in view, the invention may be further and more generally defined as consisting of the combinations of parts and elements embodied in the claims annexed to and forming part hereof and illustrated in the drawings,—wherein Figure 1 represents a sectional elevation of a little more than half of a car having my invention applied thereto; Fig. 2 represents a sectional plan view of such car; Fig. 3 a transverse sectional view through the car; Fig. 4 a top plan view of the central portion of the car; and Fig. 5 a plan view of one of the dampers whereby the distribution of air from the air distributing duct may be controlled.

Describing by reference characters the various parts illustrated in the drawings, 1 denotes generally a car body, 2 the roof, 3 the floor, and 4 the aisle between the seats 5.

6 denotes a stateroom having a doorway 7 and a lavatory 8; and 9 denotes the usual washroom having the closet 10 and the doorway 11. The lavatory 8 is provided with a vertical discharge flue 8^a having air inlet openings 8^b located above the washbowl and commode. 10^a denotes a similar discharge flue having inlet openings 10^b similarly located.

As shown herein, the means for receiving, supplying, and distributing air to the interior of the car comprises a pair of oppositely extending ducts (which may be conveniently located below the central section 70 2^a of the roof 2) said ducts communicating at their ends with the opposite ends of a distributing duct, located therebeneath, and provided with suitable damper-controlled discharge openings, the whole providing a conduit whereby the air collected and supplied by the first two ducts may be distributed in the most efficient manner to the interior of the car. The two ducts first mentioned are shown at 11 and 11^a, and each one extends from the central portion of the car to an end thereof. The duct 11 is provided at its receiving end with a laterally extending branch 12, said branch preferably resting on top of the roof 2 and having at its outer end oppositely extending inlet branches 13, the last-mentioned branches extending in the direction of the length of the car whereby air may be conducted to the receiving end of the duct 11 from one or the other of the branches 13, according to the direction in which the car is moving. In order to prevent the air which enters one of the branches 13 from passing out through the other branch without being directed into the duct 11, a damper 14, provided with an operating handle 14^a, is provided at the junction of the branches 13 and is adapted to be swung across either of the passageways connecting such branches with the lateral branch 12. The duct 11^a is similar in all respects to the duct 11, with the exception that it extends in the opposite direction from the central portion of the car to an end thereof. The parts 12^a, 13^a and 14^a are substantially identical with the parts 12, 13 and 14, respectively.

The ducts 11 and 11^a are separated from the distributing duct 15 therebeneath by means of a partition 16. This partition terminates somewhat short of the ends of the ducts 11 and 15, whereby a passageway 17

is formed around each end of the partition, and the air supplied to the ducts 11, 11^a is conducted around the ends of such partition and into opposite ends of the distributing duct 15.

It will be observed that the distributing duct 15 is located immediately above the aisle 4 and that this duct is provided with discharge outlets 17 which are so arranged 10 as to distribute the air uniformly to the interior of the car above such aisle. These openings will be of an aggregate area sufficient to supply the maximum desired quantity of air to the interior of the car. For 15 the purpose of controlling this supply, I prefer to provide these outlets with controlling dampers which may conveniently consist each of a disk 18 having radially arranged slots 18^b therein adapted to register 20 with corresponding outlet slots 18^b in the bottom of the duct 15. The dampers may be conveniently supported between the bottom of the duct 15 and flanges 19 projecting inwardly from the sides of the duct and engaging the edges of the dampers.

In order to prevent the air which is supplied to the car from unduly chilling the occupants, I provide means for heating the entering air before it may reach the distributing duct. For this purpose, I place within each of the ducts 11, 11^a one or more heating coils, indicated at 20, which coils may be conveniently supplied by the steam used to heat the car and which may 35 be conveyed in the usual heating pipes 21, 21^a. The pipe connecting the supply pipe 21 and one of the coils is indicated at 22 while the pipe connecting the coil and the return pipe is indicated at 23. Suitable 40 valves will be provided, preferably at the junction of the pipes 22 and 23 with their respective supply and return pipes, to enable as much as may be desired of the steam entering the supply pipe to be directed into 45 the heater 20. These valves are indicated conventionally at 24.

Some of the air entering the car may be conveniently and efficiently discharged through the stateroom and the lavatories. 50 At the bottom of the stateroom door 7, a grating 7^a is provided whereby the ventilating air may pass into said stateroom. Circulating through the stateroom 6 and the lavatory 8 thereof, it may escape through 55 the discharge flue 8^a, which discharge pipe may be provided with a cowl 8^c whereby the air passing through this outlet duct may be discharged in a direction the reverse of that in which the car is moving. The inlet into 60 the duct 8^a will preferably be located slightly above the commode and the basin, whereby odors will be effectively conducted away through the discharge flue.

The main discharge for the car will be 65 through the outlet shafts 25, located in the

aisle near each end of the car. Each shaft 25 will preferably be provided with a grated inlet 26 and with an outlet provided with a cowl 27. Each lavatory 9, in the closet thereof, is provided with a discharge flue 10^a 70 having the inlet openings 10^b arranged above the commode, in the same manner as the inlet openings of the shaft 8. In addition, in the lavatory or washroom proper, an additional discharge shaft 10^c may be provided 75 having inlet openings 10^d arranged in the same manner as the inlet openings 10^b and 8^b. The door to the closet or commode 10 will also preferably be provided with a grating in the bottom similar to the grating 7^a 80 and 26.

As the air which is supplied to the interior of the car must necessarily have more or less dust and cinders therein, I interpose between each inlet branch and the corresponding duct 11 or 11^a, a screen 28.

By the construction described and illustrated herein, it will be apparent that I have produced a comparatively simple and economical ventilating system for use with cars 90 as the same are at present designed; that means are provided in connection with this system for so supplying and distributing the ventilating air and to secure this result without the chilling of the air and without 95 inconveniencing the passengers; that I have provided means for efficiently and economically ventilating and removing the odors from the stateroom and general lavatories and closets; and that I have provided means whereby the air thus supplied for ventilation may be controlled as desired. If for any reason it should be desirable to cut out the ventilating system entirely, this result may be easily accomplished by merely swinging 100 the valves or gates 14 in the appropriate direction to cut off the forwardly projecting branch of the air-collecting head from the duct 11 or 11^a.

Having thus described my invention, 110 what I claim is:—

1. The combination, with a car, of a pair of air-supplying ducts extending from the central portion of the car toward the opposite ends of said car respectively, said ducts being in alinement with each other and having lateral branches at their adjacent ends, means operative by the movement of the car in either direction for supplying air to said branches, an air distributing duct beneath 115 said pair of ducts and communicating therewith at their remote ends, and means including openings in the bottom of said distributing duct for uniformly distributing the air throughout the length of the car.

2. The combination, with a car, of an air supplying duct extending longitudinally of said car, one end of said duct having a laterally extending branch an air distributing duct also extending longitudinally of said 130

car and arranged alongside of said supply duct, said distributing duct communicating with the end of said supply duct which is remote from said branch, means operative by movement of the car in either direction for supplying air to said branch, and means including openings in said distributing duct for uniformly distributing the air throughout the length of the car.

10 3. In a ventilating apparatus for cars, in combination, a pair of air supplying ducts in alinement with each other and adapted to extend longitudinally of the car, an air distributing duct arranged alongside of said supply ducts, the adjacent ends of said supply ducts having laterally extending branches and their remote ends communicating with the ends of said distributing duct, means operative by movement of the car in either direction for supplying air to said lateral branches, and means including openings arranged longitudinally of said distributing duct for uniformly distributing the air throughout the length of the ducts.

15 4. The combination, with a car, of a pair of air-supplying ducts extending from the central portion of the roof of said car toward the opposite ends of said car respectively, an air distributing duct beneath the first-mentioned ducts and with which the discharge ends of said ducts communicate, means operative by the movement of the car in either direction for supplying air to the first-mentioned ducts, and means for controlling the distribution of air from the distributing duct into the car.

20 5. The combination, with a car, of a pair

of air-collecting and supplying ducts each extending from the upper central portion 40 of the car toward an end thereof, means connected with the centrally located end of each duct and operative by the movement of the car in either direction for supplying air to said duct, an air distributing duct with 45 which the discharge ends of the first-mentioned ducts communicate, and means for controlling the distribution of air from the last-mentioned duct into the car.

25 6. The combination, with a car, of an air-collecting and supplying duct in the upper portion of the car, means operative by the movement of the car in either direction for supplying air to said duct, an air-distributing duct beneath the first-mentioned duct 55 and communicating therewith, the last-mentioned duct being provided with longitudinally spaced air-distributing dampers, and one or more outlet flues within the car and having inlets adjacent to the floor thereof. 60

30 7. The combination, with a car, of an air conduit extending longitudinally of said car and comprising a distributing compartment extending substantially the length of the car, and two supply compartments one communicating with each end of the first compartment and terminating in an air receiving end at substantially the longitudinal center of said first compartment, and means communicatively connected to the receiving 70 end of each supply compartment and arranged to collect air by the movement of the car in either direction.

In testimony whereof, I hereunto affix my signature.

DENTON K. SWARTWOUT.
